UNITED STATES PATENT OFFICE.

WILLIAM PRELLWITZ, OF EASTON, PENNSYLVANIA, ASSIGNOR TO INGERSOLL-RAND COMPANY, OF NEW YORK, N. Y., A CORPORATION OF NEW JERSEY.

UNLOADER FOR FLUID-COMPRESSORS.

1,088,366.

Specification of Letters Patent.

Patented Feb. 24, 1914.

Application filed March 11, 1907. Serial No. 361,645.

To all whom it may concern:

Be it known that I, WILLIAM PRELLWITZ, a citizen of the United States, and resident of Easton, in the county of Northampton 5 and State of Pennsylvania, have invented a new and useful Improvement in Unloaders for Fluid-Compressors, of which the following is a specification.

The object of this present invention is to 10 provide novel means for stopping the fluid compressor when the pressure in the receiver is raised to a predetermined point; permitting the compressor to remain in its loaded condition while at rest; starting the 15 compressor when the pressure in the receiver is reduced to a predetermined point; unloading the compressor just before it is started and throwing the load on to the compressor at a predetermined point after 20 it has been started. As there is always more chance for leakage of air past the piston of the fluid compressor when the compressor is at rest it is very advantageous to have the discharge valves held closed by pressure 25 during the time that the compressor is at rest so that the said discharge valves will prevent the compressed fluid from getting past the valves back into the compressor cylinder which would cause an unnecessary 30 loss of pressure fluid.

My invention consists in an unloader suitable for carrying out the above object, including a fluid pressure operated plunger and a centrifugal governor both coacting 35 as will hereinafter appear to control the movements of the auxiliary unloader valve which in turn controls the movement of the main valve of the unloader.

The unloader is shown in connection with 40 an electric motor driven fluid compressor of the "straight line" single-acting compound type and the parts are so arranged that when the pressure in the receiver rises to the desired point, the fluid pressure operated plunger will cause the breaking of the circuit in the automatic motor starting device which will stop the motor and thereby the compressor; and when the pressure falls to 45 the desired point, the fluid pressure operated plunger will cause the closing of the circuit in the automatic starting device which will start the motor and thereby the compressor. In the meantime the fluid pressure operated plunger is so arranged that it will 50 hold the auxiliary unloader valve in posi-

tion to keep the compressor loaded while at rest and until the pressure falls sufficiently to start the machine, when the auxiliary valve will be moved by the centrifugal governor into position to unload the compressor. The centrifugal governor driven from the motor will then automatically move the auxiliary valve, without disturbing the fluid pressure operated plunger, into position to again throw the load on to the compressor 60 when it has reached the desired speed.

In the accompanying drawings, Figure 1 represents an electric motor driven compressor of the "straight line" single acting compound type, certain of the parts being 65 broken away to more clearly show a discharge valve of the low pressure cylinder and a discharge valve of the high pressure cylinder, the parts being in the position which they assume at the moment when the 70 pressure has fallen in the receiver to a point where the motor is to be started, the discharge valves being shown unloaded. Fig. 2 represents the unloader in side elevation on an enlarged scale, the parts being 75 in the position shown in Fig. 1. Fig. 3 is a view of the unloader taken in a plane at right angles to Fig. 2, certain of the parts being shown in section. Fig. 4 is a detail section showing the auxiliary valve raised 80 by the movement of the centrifugal governor to a point where the load is thrown on to the compressor. Fig. 5 is a similar detail view showing the auxiliary valve held in its raised position by the action of receiver 85 pressure on the fluid pressure operated plunger for holding the presser in its loaded condition while at rest, when the pressure in the receiver is at a predetermined high point which will cause the completion 90 of a circuit which will stop the motor. Fig. 6 is a section taken in the plane of the line A--A of Fig. 3, looking in the direction of the arrows. Fig. 7 is a section taken in the plane of the line B--B of Fig. 3, looking 95 in the direction of the arrows. Fig. 8 is a detail view similar to Fig. 7, showing the position which the parts assume when the auxiliary valve is raised to throw the load onto the compressor discharge valves. Fig. 100 9 is a detail face view of the auxiliary unloader valve, and Figs. 10 and 11 are detail views of the spring-actuated mechanism applied to the centrifugal governor for returning the auxiliary valve to the limit of 105 110

its downward movement when released by the fluid pressure operated plunger, said spring-actuated mechanism being also used for exerting the proper tension against the upward movement of the auxiliary valve.

The electric motor for driving the compressor is denoted as a whole by 1 and its shaft by 2. The fly wheel 3 of the compressor driving crank shaft is driven from the electric motor 1, which wheel is provided with a driving pulley 4 from which the pulley 5 of the centrifugal governor of the unloader is driven by a suitable belt 6.

The horizontal shaft 7 of the centrifugal governor which carries the pulley 5, has a bevel gear connection 8, 9, with the rotary hollow member 10 of the centrifugal governor the branches 11, 12 of which form pivots 13, 14, for the arms 15, 16, of the weights 17, 18, of the governor, which arms control the rising and falling movements of the auxiliary valve operating rod 19, the upper end of which rod is connected to the auxiliary unloader valve 20. A spring 21 tends to limit the movement of the weights away from each other when the governor is being rotated. Another spring 22 is arranged in position to engage one arm 23 of a rock lever, the other arm 24 of which is arranged in position to bear upon projections 25 on the movable governor rod 19 for tending to hold the rod and thereby the auxiliary unloader valve 20 at the limit of its downward movement and for resisting the upward movement of the rod to the desired extent. The unloader bracket 26 is provided with a cylinder 27 within which the fluid pressure operated plunger 28 is fitted to rise and fall. This plunger 28 has a lost motion connection with the auxiliary unloader valve 20 so that when the plunger 28 is at the limit of its downward movement, the auxiliary valve 20 may be moved to the limits of its movement by the centrifugal governor without affecting the movement of the plunger 28. This lost motion connection is herein shown as being provided for by having the plunger provided with a downwardly extended shank 29 having a head 30 located within a recess 31 in a hollow cap 32 screwed into the outer end of the auxiliary valve.

The plunger 28 is normally held at the limit of its downward movement by the usual weighted lever 33 and interposed pin 34. The weighted lever 33 is provided with two contacts 35, 36, the said contacts being arranged to alternately contact with the points 37, 38 for throwing the current into the automatic motor starting device 38*, when the contact 35 engages the contact 37, for starting the motor; and for shutting off the current from the motor starting device when the contact 36 engages the contact 38. This motor starting device is of the usual

construction where the engagement of one set of contacts will start the device and the engagement of another set of contacts will stop the device. The required amount of friction may be imparted to the lever 33 at its pivotal connection on the unloader bracket 26.

The auxiliary valve 20 is fitted to slide in a partition which divides the space beneath the plunger 28 into upper and lower chambers 39, 40 in open communication with each other through one or more vertical holes 41* through said partition and in open communication with the receiver (not shown herein) through the port 39*.

The face of the auxiliary valve 20 is provided with two bridge ports 41, 42 and two through ports 43, 44. Three passages 45, 46, 47, lead from the face of the auxiliary valve 20, the passage 46 leading to atmosphere, the passage 45 leading to the space within the main valve box at one side of the main valve piston 48 and the passage 47 leading to the space at the other side of the said piston 48. The through ports 43, 44, in the auxiliary valve 20 are connected to the chamber 49 between the heads of the main valve piston 48 through passages 50, 51.

The main unloader valve is denoted by 52 and it is provided with two bridge ports 53, 54 and the main valve box is provided with two exhaust ports 55, 56, to atmosphere. This box is further provided with ports 57, 58 for the passages leading respectively from the intercooler, not shown herein, through the pipe 59 and from the back of the low pressure discharge valve 60 through the pipe 61. The main valve box is further provided with a port 62 for the passage which leads from the back of the high pressure discharge valve 63 through the pipe 64. A pipe 65 leads from the receiver, not shown herein, to the space 49 between the heads of the main valve piston 48 for supplying receiver pressure to said space.

When the auxiliary valve 20 is at the limit of its downward movement, its bridge port 41 will open communication from the space at one end of the main valve piston 48 to atmosphere through the passages 46, 47, and its through port 43 will open the space at the other end of the piston to receiver pressure through the passages 45, 50. This will move the main valve piston into the position shown in Figs. 6 and 7 and thereby unload both the high and low pressure discharge valves by opening the backs of the said valves to atmosphere through the ports 62, 54, 56 and the ports 58, 53, 55, as is common in this type of unloader.

When the auxiliary valve has been moved to the limit of its upward movement, its bridge port 42 and through port 44 will open the passages so as to reverse the movement

of the main valve piston 48 as shown in Fig. 8, thus moving the main valve into the position to bring the ports 57, 58, of the intercooler and low pressure discharge valve passage into open communication through the bridge port 53 and bring the port 62 of the high pressure discharge valve passage into open communication with the space 49 having therein receiver pressure.

10 In operation, as the pressure lowers in the receiver the fluid pressure operated plunger 28 will move downwardly under the weight of its lever 33 until the automatic starting device is started by the engagement of the 15 contacts 35, 37, which starting device will then start the motor. This downward movement of the plunger 28 will also permit the auxiliary valve to be moved to the limit of its downward movement, by means of the 20 centrifugal governor rod 19 and the spring 22. This movement will unload the backs of the low and high pressure discharge valves by reducing the pressure on the backs of these valves. This is accomplished by 25 opening the back of the high pressure discharge valve to external atmosphere through the pipe 64 and ports 62, 54, 56, and opening the back of the low pressure valve to external atmosphere through the pipe 61 and 30 ports 58, 53, 55. It will thus be seen that the discharge valves for the high and low pressure cylinders are unloaded to render the compressor inoperative just before the motor is started by the automatic starting 35 device. After the motor has been started and the compressor gains speed, the weights of the governor, owing to their centrifugal action, will raise the rod 19 and thereby their auxiliary valve into the position shown in 40 Fig. 4. This will throw the load onto the backs of the high and low pressure discharge valves by opening the back of the high pressure discharge valve 63 to the pipe 65 leading to the receiver through the pipe 64, port 45 62 and chamber 49. At the same time, the back of the low pressure discharge valve 60 will be loaded by opening the back of this valve to the pipe 59 leading to intercooler pressure through the pipe 61 and ports 58, 53, 57. This loading of the discharge valves of the compressor and thus rendering the compressor operative is accomplished without moving the fluid pressure operated plunger 28. As the pressure in the receiver rises, 55 it will raise the plunger 28 and through it the weighted lever 33. When a predetermined high pressure has been reached, the motor starting device will be stopped by the engagement of the contacts 36, 38, thus stopping the motor. As the motor comes to rest and the governor stops its action, the auxil-

iary valve is held in its raised position as shown in Fig. 5, by receiver pressure, thus keeping the load on the discharge valves of the compressor until the pressure in the receiver falls to a point where it is necessary to again start the machine.

65 While I have shown my unloader applied to a fluid compressor of the "straight line" single acting compound type, it is to be understood that I do not limit myself to its application to this particular type of compressor as the unloader may also be applied to compressors of other types such, for instance, as single stage compressors or double acting compound compressors.

70 What I claim is:

1. A motor driven fluid compressor and an unloader therefor including a fluid pressure operated device for stopping and starting the motor and for holding the compressor in its loaded condition while at rest, and mechanical means driven from the motor for automatically unloading the compressor before the compressor is started and for throwing the load on to the compressor at a predetermined point after the compressor is started.

80 2. A fluid compressor and an unloader therefor including a valve for controlling the loading and unloading of the compressor, a mechanical means for moving the valve to cause it to unload the compressor before the compressor is started and to throw the load on to the compressor at a predetermined point after the compressor is started and a fluid pressure operated plunger having a lost motion connection with the valve for holding the valve in its position for maintaining the compressor in its loaded condition while the compressor is at rest.

90 3. A fluid compressor and an unloader therefor including a valve for controlling the loading and unloading of the compressor, a centrifugal governor for moving the valve to cause it to unload the compressor before the compressor is started and to throw the load on to the compressor at a predetermined point after the compressor is started, and a fluid pressure operated plunger having a lost motion connection with the valve for holding the valve in its position for maintaining the compressor in its loaded condition while the compressor is at rest.

95 In testimony that I claim the foregoing as my invention, I have signed my name in presence of two witnesses, this 8th day of March 1907.

100 WILLIAM PRELLWITZ.
